UNITED STATES PATENT OFFICE.

JOSEPH WILLIAM LE MAIRE, OF PITTSFIELD, MASSACHUSETTS.

PRIMING DEVICE.

Application filed October 21, 1920. Serial No. 418,523.

To all whom it may concern:

Be it known that I, JOSEPH W.M. LE MAIRE, a citizen of the United States, and resident of the city of Pittsfield, in the county of Berkshire and State of Massachusetts, have invented certain new and useful Improvements in Priming Devices, of which the following is a specification.

The present invention relates to improvements in starting devices for internal combustion engines, and more particularly to that type of starting device which is intended to be used with engines upon motor vehicles, although it will be understood that it is applicable to engines used otherwise.

The main object of the invention is to provide a simple and inexpensive device, by the use of which a sufficient quantity of gasoline, to prime the engine, may be introduced into the cylinders of the engine, without the necessity of opening the hood of the motor vehicle to turn the pet-cocks of the various priming cups.

Another object of the invention is to construct a priming device in the form of a pump, the piston of which acts at the same time as a valve, closing the communication between the engine and the fluid containing tank of the priming device.

With these and other objects in view, which will more fully appear as the nature of the invention is better understood, the same consists in the combination, arrangement and construction of parts hereinafter described, pointed out in the appended claim and illustrated in the accompanying drawings, it being understood that many changes may be made in the size and proportion of the several parts and details of construction within the scope of the appended claim, without departing from the spirit or sacrificing any of the advantages of the invention.

One of the many possible embodiments of the invention is illustrated in the accompanying drawings, in which:—

Figure 1 is a longitudinal vertical section taken through a priming device constructed in accordance with the present invention; and Fig. 2 is a front elevation of the same.

In the drawings, the numeral 10 indicates a reservoir, adapted to contain a suitable liquid hydrocarbon, such as gasoline, which is filled into the said reservoir through a flared opening 11, closed by a plug 12, the latter being provided with a vent-hole 13.

This reservoir is attached in any suitable manner to the dash-board 14 of the vehicle, when the engine is applied to a motor vehicle, and is preferably disposed below the engine hood. The reservoir is provided with a small fuel outlet 15, communicating with the cylinder 16 of a pump, that is shown in the drawings as being made integral with the said reservoir, although it may be secured thereto in any suitable manner. The fuel outlet is formed near the front head 17 of the pump cylinder, the said front head being provided with a nipple 18, with which is joined a pipe 19, the latter being connected, preferably, with the intake manifold of the internal combustion engine, with which the priming device is intended to co-operate.

In the pump cylinder is mounted a piston 20 upon a piston rod 21. This rod extends through the rear head 22 of the pump cylinder and terminates in a handle 23. The piston may be of any suitable construction and of any suitable material, for instance cork. This cork may be drawn over the piston rod and held thereon by disk stops 24 and 25, the latter being secured to the said rod in any suitable manner. In front of the stop 24 is mounted a packing member, 26 in the form of a washer 26 of any suitable material. The front end of the piston rod is screw-threaded, as shown at 27, the said threads being adapted to mesh with those of the pump outlet 28 in the cylinder head 17. A stop 29 is carried by the piston rod, said stop being adapted to co-operate with the rear head 22 and serving to limit the suction stroke of the piston.

The operation of this device is as follows: In the positions of the elements shown in Fig. 1 of the drawings, the packing washer 26 snugly fits against the inner face of the front head 17 of the cylinder and the piston 20 covers the fuel outlet 15 of the tank 10, the threads of the piston rod meshing with those of the pump outlet. The communication between the tank and the engine manifold is thus closed. In order to operate the device, the piston rod is first turned anti-clockwise in order to unmesh the threads on the rod from the threads in the pump outlet. The piston is then drawn rearwards until the stop 29 abuts against the cylinder head 22. Fuel will thus pass from the reservoir 10 into the pump cylinder. The piston is held for a few moments at the end of

its suction stroke, in order to allow a substantial quantity of liquid to flow through the small fuel outlet 15 into the pump cylinder. The piston is then moved quickly in 5 the opposite direction, that is to say upon its expelling stroke. The fuel in the pump cylinder is thus injected through the pipe 19 into the intake manifold, from which it is drawn into the cylinders of the engine. 10 When the piston has reached the end of its expelling stroke, it is turned clockwise to screw the piston rod into the pump outlet, so as to bring the packing washer 26 in proper engagement with the inner face 15 of the front head 17 of the pump cylinder.

Although a single operation of the primer should be sufficient under ordinary conditions, the operation can be repeated as often as desired according to the requirements.

20 What I claim is:

A priming device for internal combustion engines, comprising a reservoir for contain-

ing a supply of liquid hydrocarbon, a pump cylinder communicating with said reservoir through an opening adjacent the front head 25 of said cylinder, said front head being provided with a screw-threaded pump outlet, a piston in said cylinder, a piston rod connected with said piston having a screw-threaded portion projecting in front of said 30 piston and adapted to engage said screw-threaded pump outlet, thereby closing said outlet and holding said piston against accidental movement, said piston covering said opening when held by the engagement of 35 said rod and cylinder head against movement, and a packing washer upon said piston rod adapted to bear against the face of said cylinder head.

Signed at Pittsfield in the county of Berkshire and State of Massachusetts, this 25th day of September, A. D. 1920.

JOSEPH WILLIAM LE MAIRF
